UNITED STATES PATENT OFFICE.

JOSEPH JULES MAURICE FRICOTEL AND JEAN JOSEPH HERRBURGER, OF PARIS,
FRANCE.

WIND-CHEST FOR MECHANICAL PIANO-PLAYERS.

1,367,543.

Specification of Letters Patent.

Patented Feb. 8, 1921.

Application filed January 8, 1920. Serial No. 349,222.

To all whom it may concern:

Be it known that we, JOSEPH JULES MAURICE FRICOTEL, a citizen of the French Republic, and JEAN JOSEPH HERRBURGER, a citizen of the French Republic, both residing at No. 16 Rue de l'Evangile, Paris, France, have invented certain new and useful Improvements in Wind-Chests for Mechanical Piano-Players, of which the following is a specification.

This invention consists in improvements in the wind chests of mechanical apparatus for playing the piano or any other instrument, operated by a vacuum by means of 15 perforated paper or cardboard.

In such apparatus it is known that the entrance of air that occurs when a perforation in the music sheet comes in front of a hole in the cylinder or tracker board, causes a valve 20 to rise and establish communication between a vacuum chamber and a bellows whose lever causes the production of the note. By the term "wind chest" is meant all of the vacuum chambers upon which are fixed valve 25 chambers that communicate through a suction pipe with the bellows. In apparatus made of metal constructed up to the present, the fixing of the valve chambers and of the suction pipes upon the vacuum chambers is 30 effected by means of a flanged joint fixed by screws and covered with skin or blotting paper, or by a mortise joint or by a rubber tube connection. These joints or these mortises are never tight and give rise to permanent 35 leakages of air into the vacuum chambers, thereby entailing the consumption of a considerable amount of power for maintaining a suitable vacuum in these chambers. The rubber tubes have also drawbacks; they be- 40 come hard and crack. Moreover, these apparatus comprise generally parts made of wood or cast metal which renders them very bulky and difficult to accommodate inside a piano; the wood works loose and becomes de- 45 formed so as to interfere with their proper working.

The object of the present invention is to remedy those drawbacks. This object is achieved by making the wind chest entirely 50 of metal in which the fixing of each valve chamber upon the vacuum chamber is effected by a tight circular beading. This beading can serve at the same time as a seat for the valve. The metal part serving to form 55 the beading may form one piece either with

the valve box or the valve chamber, or it may consist of a separate ring. The valve box has a peculiar form hereinafter described affording a perfect guidance with the minimum of friction. The valve chamber and the suction duct form a single casting made of two pieces of stamped metal. The two pieces are identically similar, thus facilitating mass production. The improved apparatus thus constituted has a 65 very small bulk; the valves are easily erected and inspected, and their guidance is perfect.

A constructional form of the improved wind chest is hereinafter described by way 70 of example and illustrated in the accompanying drawings with two modifications of the beading device.

Figures 1 and 2 illustrate a part of the improved wind chest respectively in sec- 75 tional elevation and in plan, the latter view after removal of the upper portion of the valve chamber and valve.

Fig. 3 illustrates the valve box before the beading operation.

Figs. 4 and 5 illustrate modifications of 80 the beaded joint.

Wind chests of the character referred to herein commonly comprise a plurality of superposed vacuum chambers, and, since 85 ordinarily they are all exactly alike, only one thereof is illustrated in the accompanying drawings. Each vacuum chamber consists of a rectangular metal duct 1 in the upper part of which are pierced a certain 90 number of apertures 2. Upon each aperture there is fixed the lower part 3 of a box made in two pieces forming a valve chamber and a suction duct which is pierced with a corresponding hole. The fixing is ef- 95 fected by means of the valve box 4 (Fig. 3) prolonged by a tube 5 which engages in both of the two apertures and is fixed by beading in such a manner as to form a flanged edge 6 bent back inside the vacuum chamber 1. 100 The air-tightness of such a mode of connection will be very readily understood.

The valve box 4 comprises a certain number of inwardly projecting flutes 7 and apertures 8 pierced near its base. The valve 105 9 rests in this box and is guided accurately and without appreciable friction by the flutes 7. The upper part 10 of the valve chamber is identical in shape to the lower part 3, and is fixed upon the latter by screws 110

that connect the two flanged edges together with a joint of skin or blotting paper. It is pierced with an aperture 11 above the valve. The other parts are those that are usually found in this kind of apparatus, namely: a box 12 which is provided with an air pipe 13 and is fixed permanently upon the lower face of the vacuum chamber 1 beneath an aperture closed by a tight diaphragm 14 supporting a disk 15 connected to the valve 9 by a stem 16, and a bellows 17 fixed to the lower part 3 of the valve chamber and communicating with it through an aperture 18, and carrying the lever 19 that controls the striking of the corresponding note of the piano or other instrument.

In the modification of the beading joint illustrated in Fig. 4, the valve box 20 is pierced with an aperture 21 of the same diameter as the aperture in the valve chamber 3 and the vacuum chamber 1. A flat eyelet 22 provided with a cylindrical edge 23 is fixed by beading by being folded back inwardly at 24 so as to fix the three parts together.

In the modification of the beading joint shown in Fig. 5, the lower part of the chamber 3 has a cylindrical edge 25 which is beaded upon the vacuum chamber 1 by being bent back at 26.

It will be seen that in this improved wind chest the vacuum chamber 1 is absolutely tight because it comprises only one tight beading connecting it to the valve chamber. The joint of the box 12 whose opening is closed by the tight diaphragm 9 can readily be made tight and remain tight because there is no need to dismount it. The joint between the two halves 3 and 10 of the valve chamber is made by means of screws

in such a manner as to allow of easy inspection and replacing of the valves 9. Only a slight inconvenience can be caused by it not being perfectly tight, because this valve chamber communicates with the vacuum 45 chamber only during the very short periods of the lifting of the valve 9.

What we claim is:—

1. A wind chest for a mechanical apparatus for playing the piano and like instruments, comprising metal vacuum chambers and valve chambers fixed on each vacuum chamber by a tight beaded joint forming a valve seat, and above each beaded joint a valve box formed with inwardly projecting vertical flutes, pierced with holes at its base; each valve chamber which constitutes at the same time a suction duct, being made of two superposed flanged parts of identically similar shape connected together by 55 screws.

2. A wind chest for a mechanical apparatus for playing the piano and like instruments, comprising metal vacuum chambers and valve chambers fixed on each vacuum 65 chamber by a tight beaded joint forming a valve seat, and above each beaded joint a valve box formed with inwardly projecting vertical flutes, pierced with holes at its base and formed with a lower flange or edge 70 serving to form the beaded joint; each valve chamber which constitutes at the same time a suction duct, being made of two superposed flanged parts of identically similar shape connected together by 75 screws.

In testimony whereof we have signed our names to this specification.

JOSEPH JULES MAURICE FRICOTEL.
JEAN JOSEPH HERRBURGER.
